UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed January 24, 1929. Serial No. 334,692.

This invention relates to improvements in car construction.

An object of this invention is to provide a combined locking and center pin construction for body and truck bolsters of railway cars, of rugged design, including a pin having a substantial shank portion to resist shearing and full head members at both ends thereof having shouldered engagement with the body and truck bolsters to securely lock the bolsters together against separation in a vertical direction.

Another object of the invention is to provide a combined locking and center pin having heads at opposite ends thereof, each of the heads having a shank portion formed integral therewith, both of the shank portions extending into the center pin opening of the bolster and being interlocked with each other to prevent endwise separation.

A still further object of the invention is to provide a combined locking and center pin for body and truck bolsters having head members at opposite ends thereof which are in shouldered engagement with the bolsters to prevent separation, one of said heads having a tubular sleeve portion formed integral therewith, extending through and fitting the center pin openings of the bolsters, and the other head having an integral shank portion telescoped within the sleeve and fitting the same, the shank and sleeve together forming the complete shank of the pin and being locked to each other against endwise separation.

Other and further objects of the invention will more clearly appear from the description and claims hereinafter following.

In the drawing, forming a part of this specification, Figure 1 is a top plan view of a portion of a body bolster of a railway car, illustrating my improvements in connection therewith. Figure 2 is a vertical sectional view, corresponding substantially to the line 2-2 of Figure 1. Figure 3 is a horizontal sectional view, partly broken away, corresponding substantially to the line 3-3 of Figure 2. Figure 4 is a side elevational view of a member forming a part of my improved center pin. And Figure 5 is a de-

tailed perspective view of a U-shaped locking element employed in connection with my improved center pin construction.

In said drawing, 10 designates a portion of the body bolster of a railway car and 11 a portion of the cooperating truck bolster. The body bolster has the usual top and bottom web members connected by an integral tubular section 12 which accommodates one of the heads of the center pin. The truck bolster 15 also has the usual top and bottom web members and transverse spaced walls, defining a pocket 13 which accommodates the head at the bottom end of the pin. The body bolster is provided with a bearing projection 14 at the bottom thereof which has a spherical bearing surface cooperating with a similar bearing surface on a bearing plate 15 seated in a pocket 16 at the top of the truck bolster.

In carrying out my invention, I provide the body and truck bolsters with aligned center pin receiving openings 17 and 18, respectively, the opening 18 of the truck bolster extending through the bearing plate 15. The pin receiving openings of the two bolsters and the bearing plate are preferably of the same diameter.

The sleeve-like portion 12 and the pocket 13 of the two bolsters are of larger diameter than the pin receiving openings, thereby providing pockets having annular shoulders adjacent the pin receiving openings, forming retaining means cooperating with the heads at the opposite ends of the center pin.

My improved center pin proper comprises an outer member A, an inner member B, and a locking element C. The members A and B of the center pin are secured together against endwise separation and together form a substantially solid pin member.

The member A comprises a tubular or sleeve-like shank portion 38 having a relatively heavy head member 19 formed at the upper end thereof. The tubular portion 38 is of such an exterior diameter as to fit the pin receiving openings 17 and 18 of the bolsters and extends entirely through said openings, as most clearly shown in Figure 2. The head 19 of the sleeve 38 has engagement with the annular shoulder of the body bolster, 100

thereby preventing downward movement of the member A. The bore of the tubular portion extends into the head 19 and is formed with diametrically opposed spaced interior ribs 20—20 on the opposite side walls thereof. 5 As shown in Figure 3, the ribs are spaced apart to provide diametrically opposed vertically extending slots or guide-ways 21—21 for a purpose hereinafter pointed out. The upper wall of the head 19 is provided with 10 openings 22—22 which register with the slots 21.

The member B of the center pin comprises a head portion 23 and an integral shank 24. 15 The shank 24 is of such a size as to telescope within the bore of the tubular member 38 and is provided with spaced lugs 25—25 on diametrically opposite sides thereof, which are adapted to interlock with the ribs 20 of the member A. The lugs 25 are of such a width that they will pass freely through the slots 21 when the member B is telescoped with the member A. The shank portion 24 is flattened on opposite sides, as indicated at 26—26. The 20 shank 24 is preferably rounded off adjacent the head 23 and the bottom end of the tubular portion of the member A is similarly rounded off to fit said shank portion. The head 23 cooperates with the annular shoulder of the 25 truck bolster to prevent upward movement of the pin. When the shank of the member B has been telescoped within the tubular portion of the member A and the lugs 25 brought into registration with the openings between 30 the ribs 20, the members A and B are rotated relatively to each other so as to engage the lugs between the ribs, thus bringing the parts in the position shown in the drawings, reference being made especially to Figure 3. 35

40 When in this position, the flat sides 26 of the member B are in registration with the slots 21 of the member A and in effect form walls opposing the outer walls of said slots.

The locking element C is in the form of a 45 U-shaped clip, having spaced arms 27—27 which are disposed on opposite sides of the shank of the member B and fit within the slots 21 of the member A. The arms 27 have flat inner faces which bear on the flat sides 26 50 of the shank 24 of the member B and closely embrace said member.

As will be evident, the element C thus locks the members A and B together against relative rotation, thereby preventing separation 55 of the lugs 25 and the ribs 20. In applying my improved locking pin to the body and truck bolsters of a car, the member A is inserted downwardly through the pocket of the body bolster and the sleeve portion 38 there- 60 of engaged within the pin receiving openings 17 and 18 of the bolsters. The member B is then applied by inserting the same through the pocket of the truck bolster and bringing the lugs 25 thereof into registration 65 with the slots 21 of the member A. The shank

of the member B is forced upwardly through the tubular portion of the member A until limited by engagement of the head 23 with the bottom end of the member A, whereupon the lugs 25 will be in registration with the spaces between the ribs 20. The members A and B are then given a quarter turn with respect to each other to engage the lugs between the ribs 20, thus interlocking the members A and B against endwise movement with 70 respect to each other. The retaining element C is then applied through the pocket of the body bolster, the arms 27 thereof being inserted through the openings 22 of the head 19 and forced downwardly into the slots 21 of the bore of the member A, thereby interlocking the parts against rotation as hereinbefore pointed out. 75

To remove the locking pin from the bolsters, the retaining element C is withdrawn through the pocket of the body bolster and the member B is given a quarter rotation so as to register the lugs thereof with the slots of the member A and it may be then withdrawn through the pocket of the truck bolster. 80

From the preceding description, taken in connection with the drawings, it will be evident that I have provided an exceedingly rugged locking center pin construction wherein the center pin is provided with full 95 head members at opposite ends thereof which effectively interlock the bolsters against vertical separation and, further, the telescoped arrangement of the shank portions of the members of the pin provide a substantially solid construction which offers the maximum resistance against shearing, thereby preventing separation of the bolsters in case of emergency by failure of the center pin, thereby reducing the danger of telescoping 100 of cars in case of collision. 105

While I have herein shown and described what I consider the preferred manner of carrying out my invention, the same is merely illustrative and I contemplate all changes and 110 modifications which come within the scope of the claims appended hereto.

I claim:

1. In car construction, the combination with body and truck bolsters having aligned center pin receiving openings; of a center pin provided with heads at opposite ends thereof having shouldered engagement with the body and truck bolsters, respectively, each of said heads having a shank portion formed thereon, one of said shank portions being in the form of a sleeve and the other shank portion being telescoped within said sleeve, said shank portions respectively extending through the openings of both bolsters and being locked together against endwise separation and together forming the complete shank of the pin. 115

2. A center pin for connecting the body and truck bolsters of railway cars provided 120

with aligned center pin shank receiving openings, said pin having heads at opposite ends thereof, one of said heads having a sleeve-like shank portion formed integral therewith and the other head being secured to said sleeve-like shank by a connecting element telescoped within said sleeve-like shank and held against endwise movement with respect to the same, said connecting element and sleeve together forming a substantially solid member extending through the openings of both bolsters functioning as the shank proper of the center pin.

3. In car construction, the combination with body and truck bolsters having aligned center pin openings and shoulders adjacent said openings; of a sleeve member having a head at one end, said head cooperating with the shoulder of one of said bolsters and said sleeve extending through the pin receiving openings of the bolsters and fitting the same, and a member having a head and a shank portion, said last named head cooperating with the shoulder of the other bolster and said shank being telescoped within the sleeve and extending past the meeting faces of the bolsters to resist shear, said sleeve and shank being locked against endwise separation.

4. In car construction, the combination with body and truck bolsters having aligned center pin receiving openings and a retaining shoulder adjacent each opening; of a center pin having heads at opposite ends thereof cooperating with the retaining shoulders of the body and truck bolsters, respectively, said pin including the tubular member rigid with one of the heads and fitting said pin receiving openings of both bolsters and a solid connecting member telescoped within said tubular member and extending through the pin opening of one bolster and into the pin opening of the other bolster, said connecting member being locked against endwise separation with respect to said tubular member, said connecting member having the other head formed thereon.

5. In car construction, the combination with body and truck bolsters having aligned center pin receiving openings, each opening having a retaining shoulder adjacent thereto; of a center pin having heads at opposite ends thereof cooperating with the retaining shoulders of the body and truck bolsters, respectively, said pin including a sleeve member having one of the heads formed thereon and fitting said pin receiving openings and a solid filler member telescoped within said sleeve member and projecting through the center pin openings of both bolsters, said filler member being locked against endwise separation with respect to said sleeve member, said filler member having the other head of the pin formed thereon.

6. In car construction, the combination with body and truck bolsters having aligned

center pin openings; of a center pin having head members at opposite ends thereof having shouldered engagement with the bolsters to prevent separation of the same, said pin having a shank member formed on each of the heads thereof, said shank members each being of such a length as to extend through the openings of both bolsters, one of said shank members being hollow and having the other shank member telescoped therewithin, and cooperating means on said shank member for interlocking the same against endwise separation.

7. In car construction, the combination with body and truck bolsters having aligned center pin receiving openings and a retaining shoulder adjacent each opening; of a center pin having heads at opposite ends thereof cooperating with the retaining shoulders of the body and truck bolsters, respectively, each of said heads having a shank member formed integral therewith, one of said shank members being hollow and telescoped over the other shank member, said shank members having cooperating means thereon for interlocking the same against endwise separation, said locking means being rendered operative by relative rotation of said shank members, and means for locking said shank members against relative rotation.

8. In car construction, the combination with body and truck bolsters having aligned center pin receiving openings and a retaining shoulder adjacent each opening; of a center pin having heads at opposite ends thereof cooperating with the retaining shoulders of the body and truck bolsters, respectively, said pin including a tubular member fitting said pin receiving openings and having one of the heads of the pin formed thereon, and a connecting member telescoped within said tubular member and having the other head of the pin formed thereon, a bayonet slot connection between said tubular member and connecting member to lock the same against endwise separation; and means for locking said tubular member and said connecting member against relative rotation while permitting bodily rotation of the pin with respect to the bolster.

9. In car construction, the combination with body and truck bolsters having aligned center pin receiving openings and a retaining shoulder adjacent each opening; of a center pin having heads at opposite ends thereof cooperating with the retaining shoulders of the body and truck bolsters, respectively, said pin including a tubular member fitting said pin receiving opening and having one of the heads of the pin formed thereon, and a connecting member telescoped within said tubular member and having the other head of the pin formed thereon, a bayonet slot connection between said tubular member and connecting member to lock the same against

endwise separation; and a retaining element for locking said tubular member and connecting member against relative rotation.

10. In car construction, the combination with body and truck bolsters having aligned center pin openings, each bolster being provided with a shoulder adjacent its opening; of a center pin having a head at each end cooperating with the retaining shoulders of the body and truck bolsters, respectively, said pin including interengaging elements projecting respectively from said head members, each of a length to extend through the opening of one bolster and into the opening of the other bolster and together forming the shank of the pin, one of said interengaging elements having an opening therein adapted to receive said other element, the cross section of said last named element and said opening being such that said element may be inserted therethrough while in one position but is prevented from passing therethrough when given a partial turn.

11. In car construction, the combination with body and truck bolsters having aligned center pin receiving openings and a retaining shoulder adjacent each opening; of a center pin including two shank members, one of said members having a head cooperating with the shoulder of one of said bolsters, said head being provided with a projecting portion engaging within the center pin receiving openings, and the other member also having a head cooperating with the shoulder of the other bolster, said last named head having the shank member thereof provided with a locking enlargement adapted to engage within an opening provided in the shank of the first named head, said opening being provided with a locking shoulder, said enlargement and the cross section of said opening being such that the enlargement may be inserted therethrough while in one position but is prevented from passing therethrough when the shank member is given a partial turn to engage said enlargement with the locking shoulder; and means for locking said shanks against relative rotation.

In witness that I claim the foregoing I have hereunto subscribed my name this 21st day of January, 1929.

STACY B. HASELTINE.
